DESIGN FOR A COMBINED WASHING MACHINE AND DRIER

Charles E. Morgenstern, Binghamton, N. Y., assignor to Nineteen Hundred Corporation, Binghamton, N. Y., a corporation of New York

Application September 5, 1935, Serial No. 58,438

Term of patent 14 years

To all whom it may concern:

Be it known that I, Charles E. Morgenstern, a citizen of the United States, residing at Binghamton, in the county of Broome and State of New York, have invented a new, original, and ornamental Design for a Combined Washing Machine and Drier, of which the following is a specification, reference being had to the accompanying drawings, forming a part thereof, in which:

I claim:

The ornamental design for a combined washing machine and drier, as shown.

CHARLES E. MORGENSTERN.
